(No Model.)

M. O. GODDING.

IGNITER FOR GAS OR GASOLINE ENGINES.

No. 591,598.

Patented Oct. 12, 1897.

FIG. 1.

FIG. 2.

FIG. 3.

UNITED STATES PATENT OFFICE.

MILON O. GODDING, OF MONROVIA, CALIFORNIA.

IGNITER FOR GAS OR GASOLENE ENGINES.

SPECIFICATION forming part of Letters Patent No. 591,598, dated October 12, 1897.

Application filed February 3, 1897. Serial No. 621,903. (No model.)

To all whom it may concern:

Be it known that I, MILON O. GODDING, a citizen of the United States, residing at Monrovia, in the county of Los Angeles, State of California, have made certain new and useful improvements in Igniters for Gas or Gasolene Engines, of which the following is a full, clear, and exact description or specification, reference being had to the annexed sheet of drawings and to the letters marked thereon.

My invention, which relates to certain new and useful improvements in igniters applicable to gas and gasoline engines, is an electrical device for making and breaking an electrical circuit within the operating-cylinder of a gas or gasoline engine, thereby producing at each breaking of the circuit the sparks necessary for igniting the mixture of air and gas or air and gasoline.

The objects of my invention are as follows:

First. To enable a spark or succession of sparks to be produced within the cylinder of a gas or gasoline engine by operating the apparatus by hand when starting the engine into action.

Second. To enable the piston of a gas or gasoline engine to make and break an electrical circuit within the cylinder when at the termination of its inward stroke and in combination therewith to produce the compression of a spiral spring, which so soon as the piston has commenced its outward stroke by the reaction of the said spring causes the electric circuit within the cylinder to be again made and broken, thereby insuring a second spark or series of sparks for igniting the explosive mixture of air and gas or air and gasoline in the event of the same not being ignited by the contact and breaking of the electric circuit made by the inward stroke of the piston.

Third. To prevent the turning round of the fixed igniting-points of the electrical circuit within the cylinder which makes and breaks contact with the closing and opening device operated by the piston and the reaction of the spring hereinbefore referred to. This object is effected by forming a square portion on the stem of the rod which carries the contact-pieces, the said square portion of which fits into a correspondingly square hole in the insulating stuffing-box, whereby the electrical

circuit is passed through the metallic w. of the cylinder of a gas or gasoline engine.

Upon the annexed sheet of drawings, Figure 55 1 is a transverse section on the line *a a*, Fig. 3, showing the cylinder and water-jacket of a gas or gasoline engine to which is applied my improved igniting device. Fig. 2 is an end elevation of the cylinder of such engine, 60 showing the external parts of my igniting device in elevation. Fig. 3 is a horizontal section of the same end of the cylinder and water-jacket of a gas or gasoline engine, showing the piston therein and the igniting 65 device constituting my present invention.

In the figures the cylinder is marked A and the casing B, which incloses the water-jacket C. Within the cylinder the piston D operates after the manner of an ordinary gas- 70 or gasoline engine, to which the connecting-rod E is attached by the pin F in the usual manner, the outer end of the said connecting-rod E being coupled to the crank-pin and the driving-shaft of the engine. 75

Referring more particularly to Figs. 2 and 3, it will be seen that in the cover G of the engine a stuffing-box and gland H and H', respectively, are fixed, through which the rod I passes, having at its outer end a finger-piece J and at its inner end a circular metallic disk K, preferably formed of steel. The outer end of the rod I passes through a hole in the guide L, attached to the outer end of the cylinder G by bolts, as shown. Between the inner side of the guide L and the nut M upon the stem I a spiral spring N is situated, the nut being adjusted so as to compress the spring N. The tendency of the spring acting against the nut M is to force 85 the rod I inward and thereby to carry the disk K to the inner side of the contact-springs O, as shown more particularly in Figs. 1 and 8. From the arrangement shown in these figures it will be seen that when the piston 95 B moves in the direction of its inward stroke it comes in contact with the end of the stem I, thereby forcing the said stem I and the disk K against the contact-pieces O, whereby in the first place contact of the disk K with 100 the springs O is effected, while the continued motion of the piston B farther inward continues to force the disk K, thereby slightly bending the contact-springs O, the flexure of

which ultimately causes the contact-pieces O to break contact with the disk K, and thus produce an electric spark in the explosive cylinder containing the charge of mixed air and gas or mixed air and gasoline for driving the piston B outward. So soon as the piston B is moved out of contact with the inner end of the spindle I, by reason of the forward motion of the piston B, then the reaction of the spiral spring M pushes the disk K again into contact with the spring contact-pieces O and forces the disk K inward until the flexure of the spring contact-pieces O produces their release from the disk K, and thereby produces another set of sparks within the explosive chamber of the engine.

At each successive stroke of the engine the operations hereinbefore referred to are repeated. Thereby the action of the engine is maintained continuously, it being explained that although I have in the annexed drawings shown but two contact-pieces O four, six, or any other number of pairs of such contact-pieces may be used, thereby insuring the production of a sufficiently great number of sparks within the explosive cylinder of the engine, whereby the chance of failure to ignite is reduced to a minimum.

The spring electrical contact-pieces O are attached to the stems P, to which are shown attached coils of wire Q, whereby the same are connected to an electric battery or circuit supplied from a dynamo.

On referring to Fig. 3 it will be seen that on the lower end of each stem P a square portion R is formed which fits into a correspondingly square hole in the lower end of the stuffing-box formed in the insulator S. This prevents the contact-pieces O from being turned round out of their proper working position, and the stems P are respectively maintained tight in the insulating stuffing-box S by means of the glands T.

Having now described the nature of my said invention and the best system, mode, or manner I am at present acquainted with for carrying the same into practical effect, I desire to observe in conclusion that what I consider to be novel and original, and therefore claim as the invention to be secured to me by Letters Patent, is as follows:

1. The igniter for gas or gasoline engines

consisting of a stem sliding and capable of being moved round within a stuffing-box at the inner or rear end of the cylinder of a gas or gasoline engine, the said stem being provided with a disk on its inner end for making and breaking contact with two or more spring electrical contact-pieces within the cylinder; the said stem being also provided at its outer end with a spiral spring for forcing it inward in order to make and break another electrical contact when the piston has commenced its outward stroke, the said stem being also provided with a finger-piece at its outer end so that contact may be made and broken and sparks produced within the cylinder by operating the igniting device by hand at or when starting a gas or gasoline engine into operation all substantially as hereinbefore described and shown upon the annexed drawings.

2. The stem of the spring electrical contact-pieces constructed with a square portion fitting into a correspondingly square hole in the insulating stuffing-box constructed and operating substantially as set forth.

3. The combination of a stuffing-box in the end or cylinder cover of a gas or gasoline engine, the stem movable within said stuffing-box, the disk on the inner portion of said stem, the spiral spring on the outer portion of said stem, the guide for maintaining the spiral spring in its relation to said stem, the finger-piece at the outer end of said stem, the stems carrying the spring contact-pieces formed with a square portion fitting the square hole in the insulating stuffing-box for receiving the said square portion of the spring-contact-piece stems, the connection of the said contact-piece-carrying stems with a battery or circuit operated by a dynamo, the whole constituting my improved igniting device for gas or gasoline engines and operating in the manner substantially as described and shown upon the annexed drawings.

In testimony whereof I, the said MILON O. GODDING, have hereunto set my hand, this 2d day of January, A. D. 1897, in the presence of two subscribing witnesses.

MILON O. GODDING.

Witnesses:

EDWARD W. FORGY,
GEORGE A. PEARSONS.
